(57) **CLAIM**

The ornamental design for a shoe, as shown and described.

DESCRIPTION

FIG. 1 is a top front right perspective view of a shoe showing my new design;

FIG. 2 is a top rear left perspective view thereof;

FIG. 3 is a bottom front left perspective view thereof;

FIG. 4 is a bottom rear right perspective view thereof;

FIG. 5 is a top view thereof;

FIG. 6 is a bottom view thereof;

FIG. 7 is a left side view thereof;

FIG. 8 is a right side view thereof;

FIG. 9 is a front view thereof; and,

FIG. 10 is a rear view thereof.

The portions of the shoe shown in broken lines represent thread stitching.
